UNITED STATES PATENT OFFICE

CARLOS B. MIRICK, OF WASHINGTON, DISTRICT OF COLUMBIA, ASSIGNOR TO NATIONAL ELECTRICAL SUPPLY COMPANY, OF WASHINGTON, DISTRICT OF COLUMBIA, A CORPORATION OF VIRGINIA

ANTENNA LEAD-OUT INSULATOR

Application filed January 9, 1930. Serial No. 419,595.

My invention relates broadly to radio communication systems for aircraft and more particularly to the construction of an antenna lead out insulator for use in aircraft radio installations.

5 One of the objects of my invention is to provide a construction of antenna lead out insulator which may be readily installed upon aircraft in a position which enables the 10 weight or fish which connects to the end of the trailing wire antenna to be readily passed through the lead out insulator in the process of extending the antenna or reeling in the antenna at the end of a flight.

15 Another object of my invention is to provide a construction of lead out insulator which may be installed aboard aircraft with means for normally closing the lead out insulator when the trailing wire antenna is not 20 in use, the lead out fitting being readily opened to permit the reeling out of the trailing wire antenna when the radio communication system is to be placed in use during flight of the aircraft.

25 Still another object of my invention is to provide a construction of lead out insulator for installation aboard aircraft wherein a tubular member extends from a position adjacent the exterior of the aircraft to a position 30 adjacent the antenna reel within the aircraft, the tubular member being engageable by a plug for closing the tube or by a fitting through which the trailing wire antenna may be insulatingly extended from the antenna 35 reel within the aircraft to a position trailing beneath the aircraft.

A further object of my invention is to provide a construction of lead out insulator attachable to the frame or hull of an aircraft 40 for detachably receiving a plug or an insulating guide for an antenna wire for permitting the reeling out of an antenna from the aircraft during the operation of the communication system.

45 Other and further objects of my invention reside in the construction and arrangement of parts of the antenna lead out insulator described more fully in the specification hereinafter following by reference to the accompanying drawings, in which:

Figure 1 is a fragmentary cross-sectional view through a portion of the hull of a flying boat showing the attachment of the antenna lead out insulator of my invention to the hull in a position adjacent the antenna reel, with 55 a plug closing the end of the antenna lead out insulator within the aircraft; Fig. 2 is a schematic view showing the antenna lead out insulator partially broken away and in section, and showing the trailing wire antenna 60 about to be projected through the insulator with the fish or weight still housed within the antenna lead out insulator; Fig. 3 is a view of the antenna lead out insulator with the trailing wire antenna extended therefrom 65 preparatory to a reeling out or a reeling in operation; Fig. 4 illustrates the arrangement of the trailing wire antenna in its position of normal use; Fig. 5 is a cross-sectional view taken through the antenna lead out insulator 70 with parts thereof shown in side elevation; Fig. 6 is a top plan view of the antenna lead out insulator; Fig. 7 is a cross-sectional view taken through the antenna lead out insulator of Fig. 5 on line 7—7 thereof; Fig. 8 is a cross-sectional view taken through the antenna lead out insulator on line 8—8 of Fig. 5; Fig. 9 is a cross-sectional view taken through the antenna lead out insulator on line 9—9 75 of Fig. 5; Fig. 10 is a cross-sectional view 80 taken through the antenna lead out insulator on line 10—10 of Fig. 5; Fig. 11 is a cross-sectional view taken through the externally projecting portion of the antenna lead out insulator on line 11—11 of Fig. 5; Fig. 12 85 is a fragmentary vertical cross-sectional view through the antenna lead out insulator on line 12—12 of Fig. 5; Fig. 13 shows the antenna lead out insulator about to be telescopically 90 fitted into the inwardly projecting tube of the antenna lead out insulator; Fig. 14 is a perspective view illustrating the cam members under which the insertable insulator or plug is secured adjacent the interior end of the antenna lead out insulator; Fig. 15 is a vertical sectional view through the antenna lead out insulator shown partially in side elevation and illustrating the plug in position for closing the inner end of the tubular member forming part of the antenna lead out in- 1

sulator; and Fig. 16 shows the plug in the process of insertion or withdrawal from the tubular member forming a part of the antenna lead out insulator.

- 5 In installations of radio communication apparatus aboard aircraft, it has been usual to employ a trailing wire antenna in the transmission of signals from the aircraft. Reception may be carried on by the use of 10 loops or short conductors in the nature of skid fin antennæ erected upon the aircraft, or wires extending along the planes of the aircraft. However, for transmission purposes it has been found important to employ 15 a trailing wire antenna. Various forms of insulators have been proposed for passing the wire through the hull of the aircraft, but prior forms of insulators have proven defective by reason of mechanical or electrical 20 break down or by reason of the obstruction offered by the fish or weight to the passage of the trailing wire from a position interiorly of the aircraft to a position exteriorly thereof. That is to say in prior forms of lead out 25 insulators for aircraft the trailing wire with weight attached has necessarily extended outside of the aircraft in a position substantially hanging adjacent the exterior wall of the aircraft preparatory to a projecting operation. 30 In my construction of antenna lead out insulator, I provide a tubular fitting which extends from a position adjacent the exterior of the aircraft to a position interiorly thereof, adjacent the antenna reel. The tubular 35 fitting is provided with cam shaped members adjacent the interior end thereof under which the antenna lead out insulator may be engaged and locked in position, or with respect to which a dummy plug may be inserted and 40 secured in position. The tubular member is of such size that the trailing wire antenna with the weight or fish attached thereto may be projected through the tubular member or withdrawn from its projected position after 45 the transmission is completed. I provide means for locking the antenna lead out insulator through a bayonet slot connection with the tubular member. The lead out insulator maintains the antenna wire in insulated 50 spacial relation to the interior walls of the tubular member. Hardened metal bushings are provided in each end of the antenna lead out insulator for avoiding the wearing away of the ends of the insulator during the process 55 of reeling out and reeling in of the trailing wire antenna.

The fish or weight which is connected to the end of the trailing wire antenna may be of any suitable construction such as described 60 in my copending application Serial No. 412, 121, filed December 6, 1929.

The mass of the antenna weight or fish is such as to maintain the trailing wire in such position beneath the aircraft while in flight 65 as to secure a maximum vertical component

for signaling purposes. After the trailing wire is reeled in, the antenna lead out insulator is removed from the tubular member which extends from the hull of the aircraft and a dummy plug inserted in place thereof, 70 serving to substantially seal the end of the tubular member and prevent the passage of water through the tubular member to the interior of the aircraft. The tubular member is always mounted so that the upper end thereof 75 terminates substantially above the water line when the device is installed on a flying boat. The construction of the insulator is such that seepage of water into the aircraft is prevented, both by the construction of antenna lead out insulator and by reason of the construction 80 of dummy plug. Water may tend to back up in the tubular member when an amphibian plane is riding a heavy sea, or when the plane is taking off or landing but seepage 85 of the water into the aircraft is prevented by the watertight seal provided by the joint between the antenna insulator and the tubular member or between the dummy plug and the tubular member.

The antenna lead out insulator of my invention has proven highly successful and practical in its construction and while for the purposes of illustrating my invention I will describe one preferred embodiment thereof, 90 it is to be understood that modifications may be made by those skilled in the art without departing from the spirit or scope of my invention.

In the drawings, I have shown my invention as applied to a flying boat but it will be understood that my invention is equally applicable to land planes.

Referring to the drawings in more detail, reference character 1 indicates the hull of the aircraft or flying boat, floating on the surface of the water 2, the aircraft being equipped with the antenna lead out insulator of my invention. The antenna lead out insulator includes the tubular member 3 which is screw threaded into the bushing 4 provided with a flange suitably secured by rivet members 5 to the hull of the aircraft. A reel 6 carrying the antenna wire 7 is shown mounted in position above the antenna lead out insulator. In Fig. 1 the antenna lead out insulator is shown closed by the plug 9 which has a portion 10 extending longitudinally through the tubular member 3. The portion 10 of the plug 9 has an enlarged body portion 11 thereon which substantially closes the portion of the tubular member 3 which is immediately adjacent the hull 1, and checks the inrush of water when the craft is riding a heavy sea or taking off or landing.

In Fig. 1 the antenna wire is housed entirely within the aircraft and the lead out insulator is plugged. In Fig. 2 the plug has been removed from the antenna lead out insulator and the trailing wire antenna 7 hav-

ing the fish 8 connected thereto is passed through the tubular portion 3 preparatory to the projection thereof from the aircraft. The antenna lead out insulator per se, is shown at 14 partially projected into the interior of the tubular member 3, the bushing 15 of insulator 14 substantially conforming in shape to the interior cross-section of the tubular member 3. The fish or weight 8 is shown housed within the tubular member 3 preparatory to the reeling out of the antenna 7. In order to maintain control of the antenna wire 7 loops may be taken around the laterally extending portion 12 of the lead out insulator as represented at 7a.

In Fig. 3 I have illustrated the succeeding step in the reeling out of the antenna wire where the lead out insulator is locked in position with respect to the tubular member 3 and the fish or weight 8 is dropped down free of the aircraft preparatory to the reeling out operation.

In Fig. 4, the trailing wire antenna 7 is shown reeled out from the antenna reel 6 in a substantially vertical position during flight under control of the weight or fish 8.

In Fig. 5, I have shown in more detail the structure of the antenna lead out insulator wherein the laterally extending member 12 is secured by means of screws 12a to the insulated head 16 which is provided with radially projecting studs 17 set in position by means of screws 12a. The head 16 is secured to the tubular insulator 14 by means of pins 18 shown more clearly in Figs. 9 and 12. The tubular member 3 is screw threaded at each end thereof, one end engaging the internal screw threads of the flanged bushing 4 and the other end carrying the cylindrical member 19. An inwardly extending integral flange 20 is provided in the cylindrical member 19 against which the head 16 is secured. The head 16 carries cylindrical plate 23 which is centered with respect to the head 16 by lost motion connecting means constituted by screw devices 24. A gasket 25 is secured in position against a metallic washer member 26 in an annular recess formed in the head 16. A pair of bayonet members 21 and 22 are secured internally within the cylindrical member 19 by means of screws 21a and 22a. The projecting studs 17 are free to pass between the separated ends of the bayonet shaped members 21 and 22 in the insertion or removal of the insulator from the tubular member 3 and by reason of the cam shaped faces formed on the bayonet members, a substantially watertight seal may be established between the end of the tubular member 3 and the insulator which projects therein. The lower extremity of the tubular insulator 14 is fitted with the metallic terminus 27 secured in the tubular member 14 by means of set screw 27a. The antenna wire freely passes through the tubular mem-

ber 14 which has at the upper end thereof the metallic bushing 40, which is screw threaded into the insulated tubular member 14. The antenna wire 7 passes through the small bore in the bushing 40 and a similar bore in the bushing 27 as the wire is reeled out and trailed beneath the aircraft in flight. The bushing 15 which is carried by the tubular insulator 14 is pinned to the tubular insulator 14 by radially projecting pins 15a shown more clearly in Fig. 7. The size of the bushing 15 is such that the exterior end of the tubular member 3 is substantially closed against the inrush of air or water and the pressure of the water within the interior of the tubular member 3 due to impact or wave motion, substantially broken. When the antenna wire is to be extended, the fish or weight 8 is let down through the tubular member 3 which has an interior surface diameter sufficiently large to permit the weight or fish 8 to pass through. The antenna wire 7 is first threaded through the insulator 14 and then the weight 8 attached thereto. The weight 8 is then let down through the tubular member 3 and the insulator 14 projected therethrough and locked in position therein as shown in Fig. 5. When the antenna wire is to be reeled in, the wire is coiled upon reel 6 until the fish abuts against the outer extremity of the bushing 27 at the end of the insulator 14 and then the entire assembly withdrawn from the tubular member 3 to a position within the aircraft. The weight or fish 8 may be then detached from the antenna wire 7 and the antenna wire entirely coiled upon the reel 6.

To avoid the inrush of water when the flying boat is riding a heavy sea or taking off or landing, it is essential to plug the tubular member 3 and for this purpose I provide the plug shown more clearly in Figs. 15 and 16 having a laterally extending end clip 9 similar to the laterally extended portion of the antenna lead out insulator. Screws 9a pass through the head 29 and through the studs 28 which extend radially therefrom. A tubular member 10 is secured to the head 29 by laterally extending pin 34. The upper end of tubular member 10 is provided with plug 35 secured in position therein by means of pin 35a. The lower end of tube 10 is plugged as represented at 36. An annular bushing 11 similar to bushing 15 in Fig. 5 which substantially conforms to the interior diameter of the tube 3, is pinned to the tube by means of pin 11a and blocks or breaks the tendency of water to enter the tubular member 3 at high pressure.

I have characterized the device of Figs. 15 and 16 as a dummy plug. The upper end thereof has a watertight seal with respect to the upper end of the tubular member 3 with a construction similar to the construction illustrated in connection with the antenna

lead out insulator in Fig. 5. That is the lost motion plate 31 is secured in position with respect to the insulated head 29 by screw members 30 which serve to confine the gasket 32 in position adjacent the washer member 33 located in the head 29. The rubber gasket 32 expands when the head is drawn up to fill the gap between the side walls of the sleeve 19 and the head 29 to substantially close the tubular member 3. A watertight seal is provided by moving the studs 28 to the limit of their movement under the cam shaped members 21 and 22 in a manner similar to the movement of studs 17 of the antenna lead out insulator of Fig. 5. The dummy plug is placed in position at times when the antenna lead out insulator is removed, and can be readily withdrawn for the substitution of the antenna lead out insulator whenever it is required.

In radio installations upon aircraft, it very often occurs that the lead weight or fish is broken away from the end of the antenna wire. In the antenna lead out insulator of my invention it is only necessary to reel in the remainder of the trailing wire antenna, withdraw the insulator member from the housing, and renew the lead weight or fish by the attachment thereof to the free end of the trailing wire antenna, thread the wire with weight attached through the tubular member and restore the insulator in the head thereof.

While I have described my invention in one of its preferred embodiments, I desire that it be understood that modifications can be made and no limitations upon my invention are intended other than are imposed by the scope of the appended claims.

What I claim as new and desire to secure by Letters Patent of the United States is as follows:

1. An antenna lead out insulator for aircraft comprising a metallic tubular member attachable to the hull of an aircraft and extending interiorly thereof, an attachable tubular insulator removably mounted within said tubular member and projectible beyond the limits of said metallic tubular member, insulating means carried by said tubular insulator for spacing said tubular insulator from the interior walls of said tubular member, said insulator including means for guiding an antenna wire from a position interiorly of the aircraft to a position exteriorly thereof.

2. An antenna lead out insulator for aircraft, comprising a tubular member attachable to the aircraft in a position adjacent the exterior thereof, an insulator telescopically insertable through said tubular member from the interior of the aircraft and projectible beyond the limits of said tubular member with the exterior walls of said insulator spaced from the interior walls of said tubular member, and means carried by said insulator for

guiding an antenna wire therethrough to a position trailing from the aircraft.

3. An antenna lead out insulator comprising a tubular member attachable to the hull of an aircraft, a tubular insulator projectible through said tubular member, means on said tubular insulator for detachably engaging the interior end of said tubular member, insulation means carried by said tubular insulator for spacing said insulator from the interior walls of said tubular member, said tubular insulator being formed to guide a weighted antenna wire from a position within the aircraft to a position trailing below the aircraft. 70 75 80

4. An antenna lead out insulator for aircraft, comprising a tubular member attachable to the hull of the aircraft, a tubular insulator insertable through said tubular member and having means adjacent the upper end thereof for removably sealing the connection between said insertable tubular insulator and said tubular member, and means adjacent the lower end thereof for spacing said insulator from the interior walls of said tubular member, said insertable insulator having means for guiding an antenna wire from a position within the aircraft to a position trailing beneath the aircraft. 85 90 95

5. An antenna lead out insulator for aircraft comprising a metallic tubular member attachable to a position adjacent the frame of the aircraft, an insulator projectible through said tubular member, means for detachably locking said insulator adjacent the 100 interior end of said tubular member and spacing said insulator from the interior walls of said metallic tubular member, said insulator having means for guiding an antenna wire therethrough from a position interior of said aircraft to a position trailing beneath the aircraft. 105

6. An antenna lead out insulator for aircraft, comprising a tubular member attachable to the frame of the aircraft and extending interiorly thereof, a bayonet groove head on said tubular member, an insulator projectible through said tubular member and having a sleeve portion formed thereon and engageable with the bayonet groove head on 110 said tubular member for the insertion or detachment of said insulator from said tubular member, said insulator having means for guiding an antenna wire therethrough from a position within the aircraft to a position 115 120 trailing beneath the aircraft.

7. An antenna lead out insulator for aircraft comprising a tubular member attachable to the frame of the aircraft and extending to a position interiorly thereof, an insulator insertable through said tubular member and projectible beyond each end thereof, said insulator having a sleeve formed thereon adjacent each end thereof, and means carried by said sleeve adjacent the interior end 125 130

5 of said tubular member for engaging said tubular member and locking said insulator in spaced relation to the interior walls of said tubular member, said insulator having means for guiding an antenna wire therethrough from a position interiorly of the aircraft to a position trailing beneath the aircraft.

10 8. An antenna lead out insulator comprising a housing attachable to the frame of an aircraft for detachably receiving an antenna lead out insulator therethrough and a dummy plug insertable within said housing, means for detachably locking said dummy plug in a position within said housing for closing the passage of the antenna wire therethrough.

15 9. An antenna lead out insulator comprising a housing attachable to the frame of an aircraft, an insulator telescopically projectible through said housing, a hand grip connected with the interior end of said insulator, spacing means adjacent opposite ends of said insulator substantially conforming to the interior cross-section of said housing, means carried by one of said spacing means being for detachably engaging the interior end of said housing, the other of said spacing means being arranged to substantially close the exterior end of said housing.

20 10. An antenna lead out insulator for aircraft comprising a frame attachable to an aircraft, an insulator telescopically projectible through said housing, a sleeve carried by the interior end of said housing, a head carried by said insulator, a hand grip connected with said head, and means projecting from said head and engageable with parts secured to said sleeve for substantially maintaining said insulator in position within said housing with the exterior walls of said insulator spaced from the interior walls of said housing, and means carried by said insulator and aligned with the opposite end of said housing for substantially closing the entrance to the interior of said housing from the exterior 45 of the frame of the aircraft.

25 11. An antenna lead out insulator comprising a metallic tube connected with the hull of an aircraft and extending to a position within the aircraft, connecting means on the interior end of said metallic tube, a tubular insulator projectible through said metallic tube, complementary means adjacent one end of said tubular insulator for engaging the connecting means on said tube, and a laterally extending member secured to the interior end of said tubular insulator and adapted to provide a tie means around which the antenna wire may be wrapped, the antenna wire extending through said tubular insulator and having a weight thereon adapted to be passed through said metallic tube when interconnecting the complementary connecting portions of said tubular insulator and said metallic tube.

30 12. An antenna lead out insulator for the antenna wire of an aircraft comprising a conduit connected to the hull of the aircraft and extending to a position interiorly thereof through which the weighted fish of a trailing wire antenna may be freely passed, a collar formed on the interior end of said conduit, a tubular insulator projectible through said conduit to a position beyond the hull of the aircraft, and means carried by said tubular insulator for establishing an interlocking engagement with the interior end of said conduit, and laterally extending members projecting from the collar on said tubular insulator and adapted to be engaged by the antenna wire for maintaining the antenna wire in predetermined position with respect to said lead out insulator.

35 13. An antenna lead out insulator for aircraft, comprising a conduit secured to the hull of the aircraft and projectible to a position within the aircraft, a head formed on the interior end of said conduit, a tubular insulator projectible through said conduit and having a complementary head adjacent one end thereof adapted to removably engage the head on said conduit, the head on said tubular insulator having a pair of laterally extending arms providing a hand grip for removably sliding said tubular insulator longitudinally through said conduit to a position in which the head on said tubular insulator engages the head on said conduit, and means carried by said tubular insulator for spacing said tubular insulator from the interior walls of said conduit, said tubular insulator having means in each end thereof for guiding a trailing wire antenna therethrough.

In testimony whereof I affix my signature.
